United States Patent

Des. 235,908
Patented July 15, 1975

235,908

COMBINATION PLANTER AND BENCH

Wallace Rosenwach, 2 Harbor Road,
Great Neck, N.Y. 11024

Filed Feb. 4, 1974, Ser. No. 439,415

Term of patent 14 years

Int. Cl. D11—02

U.S. CL. D35—3 A

FIG. 1

FIG. 2

FIG. 3

FIG. 4

FIG. 1 is a perspective view of a combination planter and bench showing my new design;

FIG. 2 is a top plan view thereof;

FIG. 3 is a side elevational view thereof; and

FIG. 4 is a bottom plan view thereof.

I claim:

The ornamental design for a combination planter and bench, substantially as shown.
